GAS ARC LAMP

Kurt F. J. Kirsten, Seattle, Wash., assignor to
 Kirsten Lighting Corporation, a corporation of
 Washington

Application October 24, 1933, Serial No. 694,981

3 Claims. (Cl. 176—124)

This invention relates to the art of gaseous conduction lamps and has reference more particularly to a novel electrical circuit for the kindling and operation of a gas arc lamp.

5 Heretofore, in the art of gaseous conduction lamps or luminous tubes containing rare gases or metallic vapors, the chief difficulties have been in the complexity of the electrical circuit and of the equipment required in connection therewith. 10 Even the most recent achievements in the field of gas arc tubes embrace the following auxiliary devices:

First.—Directly or indirectly heated cathodes coated with a metallic oxide.

15 Second.—A source of electrical energy for heating the cathodes; usually in the form of some special low potential windings superimposed upon the main transformer which energizes the arc.

Third.—A high frequency oscillator or Tesla coil, energized from the main circuit for starting the arc.

20 Fourth.—A ballasting impedance which stabilizes the arc or which, in series with the arc of negative resistance characteristics, gives the circuit as a whole positive resistance characteristics.

Fifth.—Thermostats which retard the imposition of arc potential upon the electrodes until after the cathodes have been brought up to proper heat and which also retard and limit the functioning of the Tesla coil to the proper period of its operation.

Sixth.—Relays which, delayed by the thermostats, close the main arc circuit and open the Tesla coil circuit at the proper time and which 35 shunt out the thermostats so that they may assume their normal initial setting for again repeating this starting cycle of operations should the line potential drop or be cut off due to circuit disturbances.

40 The cost of the above equipment and the added expense of its maintenance and skill required for its assembly have stood in the way of introducing the luminous arc lamp into the field of general illumination in competition with other sources of light, such as the tungsten lamp, or in the field of advertising with the high voltage glow tube which is now used extensively in all parts of the civilized world and which owes its success to the simplicity of its circuits and small amount of 45 auxiliary equipment necessary to operate it.

With respect to the high voltage glow tube, the operating equipment consists only of a suitable impedance in series with the tube circuit to give the tube a positive resistance characteristic.

50 Usually this impedance is incorporated in the

transformer which has a secondary potential sufficiently high to start the lamp.

In view of the above stated facts, it has been the object of this invention to simplify the luminous arc tube and its supplementary circuits so that it compares favorably in cost and maintenance with the simple glow tube and its circuits. 5

It is also an object of this invention to provide a novel lamp circuit whereby use of the usually 10 employed Tesla coil and associated relays are eliminated; which also eliminates the use of costly external thermostats and their heating coil and finally, the production of a highly efficient arc lamp at a cost comparing favorably with that 15 of the glow tube.

Other objects of the invention reside in the details of construction of the circuit, the electrodes and the mode of operation of the lamp, as will hereinafter be fully described. 20

The simplification of the circuit of the luminous arc tube is made possible chiefly through use of the special cathode construction described and illustrated in my pending application filed on August 7, 1933 under Serial Number 683,985. 25 This cathode is constructed so that it is energized by the arc current itself instead of by special auxiliary circuits. In connection with this particular cathode I associate bi-metal thermostatic strips in the electrode construction 30 whereby the arc current is shunted through a conductor which, externally of the tube, connects the heating elements of the cathodes in series. Thus, the electrodes are heated as soon as the circuit is closed and when the cathode heat is 35 sufficiently high, the bi-metal strip warps from the heat and breaks the short-circuit of the arc. This sudden opening of the short-circuited arc path and of the impedance creates a rise of potential across the arc path which is sufficiently 40 high to kindle the arc.

In accomplishing the various objects of the invention, I have provided the improved details of construction, the preferred forms of which are illustrated in the accompanying drawings, where- 45 in—

Fig. 1 is a view diagrammatically illustrating the present lamp and its circuit in its simplest form.

Fig. 2 similarly illustrates the lamp and another circuit of simple form.

Fig. 3 is a diagrammatic illustration of the present lamp and its circuit including control equipment which will insure most satisfactory operation of the lamp. 50 55

Fig. 4 is a view diagrammatically illustrating an alternative arrangement.

Fig. 5 is another alternative construction using an external thermostat.

5 Fig. 6 is a diagram of another alternative construction employing an external thermostat and relay.

Referring more in detail to the drawings—

10 In each of the several views 1 designates a sealed transparent tubular vessel of glass or other suitable material filled with a rare gas or metallic vapor, or a combination of gas and vapor which is the carrier for the luminous arc. At its opposite ends the tube 1 has enlargements 2—2' shaped to best accommodate the terminal electrodes of the lamp which, respectively, are designated in their entirely by reference numerals 15 3—3'.

20 The electrodes 3—3' preferably are in accordance with the construction illustrated and described in my application filed August 7, 1933 under Serial Number 683,985, and each comprises an indirectly heated cathode enclosed by a heat conserving shield. More specifically described, 25 the cathode consists of a tubular metallic shell 3a within which is a heater coil 4. The outer end of the coil is electrically connected with the shell 3a and at its inner end is connected with a terminal wire 8 which is sealed through the end wall 30 of the lamp tube. The heat conserving shield which encloses the cathode is designated by numeral 3b and this is a cylindrical, metallic piece larger than the cathode and supported by a sealed in wire 1 used as a terminal only for processing 35 the luminous tube. The shield 3b has electrical connection at 3c with the outer end of the cathode shell 3a for the purpose fully disclosed in the above mentioned application.

40 In accordance with the present invention, as illustrated in Figs. 1, 2, and 3, in each electrode a bi-metal strip 5, functioning as a thermostatic element, is welded or otherwise fixed at one end to the heat conserving shield 3b and the movable end of this strip normally makes contact with a 45 sealed in terminal connection 6. The terminal 6 at one end of the tube and its corresponding terminal 6' at the other end of the tube are electrically connected by a conductor 9.

50 In the construction of the lamp of Fig. 1, standard line potential from a one hundred ten or two hundred twenty volt main may be applied by the closing of a switch 12, to the terminal connections 8—8' of the lamp; these terminals being connected to the switch by the conductors 8a and 8b. In this simple construction a current 55 limiting reactance, designated at 18, is included in the conductor 8a and this is so designed that the lamp operates at the desired current and that the current is not too large for the cathode heaters when the arc is shunted by the wire 9 as will 60 presently be understood.

65 The circuit of Fig. 2 differs slightly from that of Fig. 1 in that the application of electrical potential on the terminals 8—8' from the main line is through a transformer consisting of an iron core 14 with a magnetic shunt 15 which gives the transformer a high internal reactance. It includes also the primary winding 16 and auto-transformer winding 17. Current from the main 70 is applied through a switch 12 to winding 16 which has a conductor 16a leading from one side to the lamp terminal 8' and a conductor 16b leading to one end of winding 17 which, in turn, is connected at its other end by conductor 17a 75 with lamp terminal 8. The transformer here

shown is typical of the various kinds of transformers used in the luminous tube art.

The lamp circuit of Fig. 3 is an elaboration of the simple forms shown in Figs. 1 and 2. In this arrangement the terminals 8 and 8' are connected to the terminals of the secondary winding of a current limiting transformer 11. The primary winding of this transformer is connected to the power circuit through switch 12. Also in this arrangement the terminals 6 and 6' at one end and 10 the terminals 6' and 8' at the other end are shunted, respectively, by condensers 10 and 10' and interposed in the conductor 9 is a shunt impedance 9a.

15 The operation of the lamp and circuit of Fig. 3 will be first described as it simplifies the understanding of circuits of Figs. 1 and 2. Upon closing switch 12 a current from the secondary of the transformer 11 flows through the heater coil 4 of the cathode of electrode 3 and since 20 the coil 4 is electrically connected through the cathode shell and connection 3c to the heat conserving shield 3b surrounding the cathode, the current will flow through the shell and thermostatic strip 5 to terminal 6, thence through conductor 9 and impedance 9a to the terminal 6'; thermostat 5'; through electrode 3' to terminal 8' and back to the transformer secondary. The magnitude of this current depends upon the total 25 impedance of the secondary circuit, that is, upon the resistance of coils 4, the shunt impedance 9a and the internal reactance of transformer 11. 30

35 The internal reactance of the transformer is so proportioned that the short-circuit current of the secondary is only slightly larger than the normal operating current of the lamp after the arc is established.

40 A short time after closing the switch 12, the heater coils 4, will bring the cathodes to incandescent glow and by radiation of heat to the shields, the bi-metal strips 5 will warp so that their contacts with terminals 6—6' are broken. This sudden opening of the circuit through impedance 9a immediately raises the potential of the secondary of transformer 11 to its open circuit potential which is high enough to ionize the gas between electrodes 3 and 3' to establish the arc. This arc current is of sufficient magnitude to maintain the heat of the cathodes since it must also flow through the heater coils 4. The 45 thermostats 5 also remain open due to the continued heat radiation of shields 3b of the electrodes.

50 Should the energy supply be accidentally cut off from the primary of transformer 11 and be 55 reestablished with switch 12 in closed position, the arc in the tube will re-kindled automatically since, upon the circuit failure, the cathodes immediately lose their heat and the thermostats 5 close against terminals 6—6', thus re-establishing 60 the normal starting conditions of the tube. If the voltage fluctuation in the supply circuit is so rapid that full potential again exists on terminals 8 of the tube before thermostats 5 have time to close upon terminals 6—6', the gas 65 in the gap between the thermostats and their respective contacts becomes ionized allowing approximately normal current to pass through the impedance shunt 9—9a and heater coils 4 with the result that the cathodes are brought again 70 to normal emission and the arc is re-established.

75 The operation of the lamp of Fig. 2 is substantially like that of Fig. 3. It will be observed that in the arrangement of Fig. 2 there is no impedance interposed in the conductor 9 and 75

that there are no condensers shunting the terminals 6-8 and 6'-8'. It has been established that the impedance may be omitted and the terminals 6-6' connected with a wire of suitable size except in cases where the reactance of the transformer is such that the secondary short-circuit current is so large that the cathode heater wires become overheated.

The condensers 10-10' of Fig. 3 are not necessary in normal circuits but are very effective in kindling the arc at considerably lower voltages than is possible without them. Also, they eliminate the current drop in a mercury vapor tube which always occurs during the first minute after the arc is struck. Incidental to this current drop, the arc voltage also rises and it is this maximum arc potential for which the transformer 11 has to be designed. Hence if this potential rise is prevented by use of a condenser 10, the same transformer can maintain an arc during its initial burning stages in a considerably longer tube.

Therefore, the use of condensers 10-10' as in Fig. 3 has the advantage of greater tube footage for a given transformer, an increased power factor for the tube circuit, and assures a more positive kindling of the arc.

When omitting the impedance 9a and condensers 10-10' of the circuit of Fig. 3, the only equipment necessary for the operation of the tube is the provision of a transformer with sufficient internal reactance to limit the short-circuit current of the secondary to approximately the same magnitude as the normal operating current of the arc. Hence, the circuit is precisely as simple as that of the high voltage glow tube. In this connection, it will now be apparent that by the simple addition to the electrode of my above mentioned co-pending application, 40 of a thermostatic element for delaying striking of the arc until the cathodes have become heated, and by the addition of a conductor joining the two electrodes of the tube, the glow tube is changed to arc performance.

45 In an alternative construction, as disclosed in Fig. 4, the conductor 9 is located internally of the lamp tube and connects at its ends with metal hooks 20 supported by insulation 21 from the shields 3b and adapted to be connected electrically with the shield by a bi-metal thermostatic band 23 attached to the shield. In this type, the conductor serves by corona discharge to ionize the gas along the arc path to stimulate the formation of the arc when the shunt connection 50 along conductor 9 is opened.

In another modification, as shown in Fig. 5, I locate a thermostatic switch 25 in the conductor 9 externally of the tube; the conductor in this instance has direct connection through the 55 terminals 6-6' with the shields 3b. Conductors 26-27 lead from the secondary of transformer 11a to terminals 8-8' and a coil in conductor 26 applies heat to the thermostat to open the circuit through conductor 9 after the cathodes have become heated. Also, a condenser, as at 60 28, may be provided to shunt across the switch to aid in starting the arc, especially in long tubes.

Fig. 6 discloses still another alternative construction in which the shunt connection 9a between the electrodes is exteriorly of the tube and is completed through the armature 30 of a relay 31. The core 32 of the relay is surrounded by a coil 33 connected at one end by wire 34 to a 65 thermostatic strip 35 and at its opposite end by

a wire 36 to a circuit wire 37 that leads from the lamp terminal 8 to a contact 38 adapted to be engaged by the thermostatic strip 35. A wire 40 from one side of the secondary of a transformer 41 forms a heating coil 42 about the 5 thermostatic strip and fastens to the base of the strip. A wire 45 connects the other side of the secondary with terminal 8'.

In using this type of lamp, at the start, the shunt connection is closed through armature 31, 10 thus connecting the heating elements in series in the lamp circuit. Current also flows through coil 42 to wire 37 by reason of lesser resistance than is placed in the relay circuit. The coil 42 becomes heated and ultimately causes the thermostatic strip 25 to disengage terminal 38 thereby causing current to flow through relay coil and energizing the relay to open the circuit through the conductor 9a thereby causing the arc to be established in the lamp. 20

It will be quite apparent that in the present arrangement, especially of Figs. 1, 2, and 3, an arc lamp of simplified construction is provided. It is a lamp that can be made and maintained in operation at a relatively small cost especially 25 in comparison with present day gas arc lamps. It is a lamp that compares favorably with the common glow lamp in cost of construction and maintenance but which is materially better from the standpoint of illumination. The cathodes 30 are energized not by special auxiliary circuits, but by the arc circuit itself, and by use of the internally located thermostats in the cathode heating circuit, costly external thermostats and auxiliary circuits are eliminated. Thus, practically all external equipment now employed in known devices of the prior art are eliminated. 35

Having thus described my invention, what I claim as new therein and desire to secure by Letters Patent is— 40

1. A lamp of the character described comprising a sealed, transparent tubular vessel containing an ionizable gas and provided within its opposite ends with electrodes, each with a terminal extending to the exterior of the tube, a source 45 of alternating current potential with connections from opposite sides thereof, respectively, to said electrode terminals, each of said electrodes including a heating element in series with the lamp circuit, a conductor extending between the 50 electrodes exteriorly of the tube and having terminals entering the tube, an impedance element in said conductor, condensers shunted across the terminals of said electrodes and of said conductor and thermostatic strips associated with each electrode and operable at a predetermined degree of heat therefrom to open the circuit connection provided between the electrode and said conductor. 55

2. A lamp of the character described comprising 60 in a sealed, transparent, tubular vessel, containing an ionizable gas and provided within its ends with electrodes; each with a terminal connection extending to the exterior of the tube; a source of alternating current having connections leading to said terminals and through which electrical potential may be impressed on the electrodes to maintain an arc in the lamp; each of said electrodes including a cathode containing a heating element and a heat conserving shield 65 surrounding the cathode and electrically connected thereto, a conductor exteriorly of the tube and having its terminals extending into the opposite ends of the tube, thermostatic strips electrically connecting said terminals and the shields 70 75

of the electrodes, thereby to join the heating elements and shields in series with the lamp circuit; said thermostatic elements being adapted at a predetermined degree of heat to open the circuit connections provided thereby.

3. A lamp of the character described, comprising a sealed, transparent vessel containing an ionizable gas and provided within its ends with electrodes, each with a terminal connection extending to the exterior of the tube, a source of alternating current potential with connections from opposite sides leading, respectively, to opposite terminals of the lamp, a conductor exterior-

ly of the tube shunting the arc path between the electrodes and including a solenoid activated switch, a thermostatic element for closing the supply circuit, a heating coil in series with the thermostatic element and supply circuit for heating the element to open the circuit and an energizing coil for the switch through which the supply current is shunted by the opening of the circuit through the thermostatic element, thereby to open the switch in the electrode connecting conductor. 5 10
